UNITED STATES PATENT OFFICE.

ELNATHAN S. STARR, OF CORONA, CALIFORNIA.

WATER-WHEEL TURBINE.

Application filed June 6, 1927. Serial No. 196,846.

The invention primarily has for its object to provide a water wheel turbine of a simple and efficient construction in which means is provided for obtaining a maximum of force 5 from a head of water with a minimum of friction, or resistance.

In its more detailed nature the invention seeks to provide a new and improved water wheel turbine structure in which a water 10 wheel of narrow ring-like character may be employed and in which an end delivery scroll casing of peculiar design is utilized to deliver the impelling water to the wheel through a plurality of jets or nozzles formed 15 in a rib depending from the casing into a groove in the wheel above the blades or vanes thereof and which receive and deliver water from the casing at or near its greatest diameter.

With the above and other objects in view that will hereinafter appear, the invention further resides in the novel details of construction, combination and arrangement of parts, all of which will be first fully described, then be particularly pointed out in the appended claims, reference being had to the accompanying drawings, in which:—

Figure 1 is an elevation disclosing a means of adapting the invention to use.

Figure 2 is a plan view of the water wheel.

Figure 3 is an inverted plan view of the water delivering scroll casing.

Figure 4 is a detail cross section taken through a portion of the casing and water 35 wheel.

Figure 5 is a developed section taken through several blades and nozzles of the wheel and casing respectively.

Figure 6 is a horizontal section taken centrally through the scroll casing.

Figure 7 is a detail vertical half wheel section illustrating a modified arrangement of the invention.

Figure 8 is a diagrammatic sectional development of the casing illustrating a modified discharge slot arrangement.

In the drawings in which like numerals of reference indicate like parts in all of the figures, 1 indicates supporting buttresses 50 which may, if desired, be constructed to provide a water take-off or spillway 2. A central supporting column 3 is provided and a power shaft 4 is vertically mounted thereupon in any suitable end or thrust bearing 5, 55 a suitable upper end bearing 6 being also provided for the said shaft.

A turbine water wheel is secured upon the shaft 4 and includes a hub 7 keyed to the said shaft and equipped with a spider 8 for supporting the spaced peripheral rings 9 60 upon the said hub. The rings are spaced a short distance apart to provide a relatively narrow water passageway in which suitable blades or vanes 10 are mounted in spaced relation and directed reversely, or down- 65 wardly rearwardly considering the direction of rotation to be forward. The blades are curved at their upper ends as at 11 and are sharpened so as to reduce water resistance to the minimum and thereby presented axially 70 toward the water impelling nozzles herein-after described.

The blades are positioned with their upper ends short of the ring tops so as to provide an annular space or groove 12 to 75 receive the annular rib 13 depending from the casing 14. As will be observed from the drawings the casing is scroll shaped with its outer peripheral wall being circular and being of gradually diminishing cross sec- 80 tional area from its entrant end indicated at 15 into which water is received from any suitable supply pipe connected with a source of supply suitably elevated to its terminus positioned closely adjacent the said entrant 85 end.

The cross sectional area of the casing at any particular point is partially circular with flat faces or portions 16 which merge to form an angle providing an angular projection or pocket 17 into which the water directed by centrifugal force set up by its swirling motion in and around the casing. In the adaptation of the invention illustrated in Figure 1 one of the flat portions 95 16 is positioned horizontally and the rib 13 depends from that portion closely adjacent its juncture with the other flat portion and consequently is positioned for receiving wa- 100 ter from the pocket 17 through the jet ori- 105 fices 18 formed in the said rib and being projected therethrough annularly downward into the blades of the water wheel.

The orifices are of larger diameter inside the casing than they are at their discharge 105 ends and if desired a small lip 19 may be raised at the advanced side of each orifice receiving end to tend to facilitate the pas- 110 sage of water into the said orifices to be directed forcefully against the water wheel 110 blades.

Suitable supports 20 may be provided for

supporting the casing upon the buttresses 1 and a bevel gear 21 may be mounted on the shaft 4 and caused to mesh with a bevel gear 22 on any suitable power take-off shaft 23 which may be equipped with a take-off pulley 24 for applying the power set up by the rotating wheel to any desired practical use.

By providing the casing scroll-shaped with its peripheral wall forming a true circle and the gradually diminishing cross sectional area feature being provided for by changes in the inner wall dimensions, a more truly circular path for the inrushing water that will set up the least possible resistance is provided, and by providing the flat faces forming the annular pocket the water will be naturally forced into the said pocket by centrifugal force and delivered therefrom at its maximum force. Also by delivering the water from the greatest diameter of the scroll casing maximum leverage and more power is obtained with a minimum of friction or other resistance.

By forming the nozzles in the depending rib the power applying water jets or nozzles are directed toward the blades in a manner for utilizing the maximum of their power applying potentialities and by positioning the blades as indicated at substantially right angle reversely directed positions and by curving and sharpening edges of the blades into substantially axial alignment with the nozzles, means is provided for receiving the maximum force of the water jets without tendency toward waste or loss of power by waste of water over the blades and between the wheel and casing.

While I have disclosed the wheel as operating in a horizontal plane around a vertical axis it is to be understood that the same may be mounted to operate on a horizontal axis to rotate in a vertical plane without departing from the principles of the invention.

If desired the rib through which the delivery casing discharges may be formed on the outer or peripheral flat face thereof to discharge into a horizontally rotatable turbine wheel 25. Also, the discharge may be effected through slots 26 instead of the orifices if found practical. See Figures 7 and 8.

From the foregoing description, taken in connection with the accompanying drawings, it is thought that the novel details of construction, the manner of use and the advantages of my invention will be readily apparent to those skilled in the art to which it relates.

What I claim is:

1. In a device of the character described, a water delivery casing of the scroll type having a cross sectional area partially circular and having two flat portions projecting

from the circular portion and joining to form an angle, an annular rib depending from one flat portion closely adjacent its juncture with the other flat portion, and having nozzle orifices therethrough to deliver the water from the angle formed by the flat portions through said rib, and said casing having an entrant throat and a terminus and its cross sectional area gradually diminishing from the entrant throat to the terminus, the peripheral diameter of said casing remaining constant while the remaining portions thereof are diminishing to form the scroll.

2. In a device of the character described, a water delivery casing of the scroll type having a cross sectional area partially circular and having two flat portions projecting from the circular portion and joining to form an angle, an annular rib depending from one flat portion closely adjacent its juncture with the other flat portion, and having nozzle orifices therethrough to deliver the water from the angle formed by the flat portions through said rib, a rotatable water wheel having spaced ring walls, vanes between the walls and terminating short of the tops of the walls to form an annular groove to receive the depending rib whereby the nozzle orifices discharge will be directed against the vanes to rotate the wheel.

3. In a device of the character described, a water delivery casing of the scroll type having a cross sectional area partially circular and having two flat portions projecting from the circular portion and joining to form an angle, an annular rib depending from one flat portion closely adjacent its juncture with the other flat portion, and having nozzle orifices therethrough to deliver the water from the angle formed by the flat portions through said rib, a rotatable water wheel having spaced ring walls, vanes between the walls and terminating short of the tops of the walls to form an annular groove to receive the depending rib whereby the nozzle orifices discharge will be directed against the vanes to rotate the wheel, said nozzle orifices being larger at their receiving ends than at their discharge ends and directed downwardly angularly into the water wheel, and said wheel vanes being positioned at approximate right angles to the axes of the nozzle orifices and curved and sharpened at their upper ends to align with said orifices' axes as they are passed.

4. A device of the character described comprising a water delivering casing, a water turbine wheel associated with the casing, and means to take off power imparted by the wheel, said casing being of the scroll type having a cross sectional area partially circular and having an extended angular portion forming an angular peripheral pocket into which the water is forced by the centrifugal

force set up by its motion, vanes on the wheel, and nozzles for delivering water from the angular pocket against the vanes of the wheel for the purposes specified.

- 5 5. In a device of the character described, a water delivery casing of the scroll type having a cross sectional area partially circular and having two flat portions projecting from the circular portion and joining to 10 form an angle, one of said flat portions having at least one discharge opening for the purpose specified, the axis of which opening lies parallel to the other of said flat portions and inclined to the plane of the flat portion 15 in which the opening lies.

6. In a device of the character described, a water delivery casing of the scroll type having a cross sectional area partially circular and having two flat portions projecting from the circular portion and joining to 20 form an angle, an annular rib projecting from one flat portion closely adjacent its juncture with the other flat portion, and having openings therethrough to deliver the water from the angle formed by the flat 25 portions through said rib, the axes of said openings lying parallel to the other flat portion and inclined to the flat portion having the openings.

ELNATHAN S. STARR.
